(No Model.)

E. R. CAHOONE.

Over Draw Check Rein Attachment.

No. 242,506.

Patented June 7, 1881.

UNITED STATES PATENT OFFICE.

EDWIN R. CAHOONE, OF NEWARK, NEW JERSEY.

OVERDRAW CHECK-REIN ATTACHMENT.

SPECIFICATION forming part of Letters Patent No. 242,506, dated June 7, 1881.

Application filed April 11, 1881. (No model.)

To all whom it may concern:

Be it known that I, EDWIN R. CAHOONE, of Newark, county of Essex, State of New Jersey, have invented a new and Improved Overdraw Attachment for Check-Reins; and I do hereby declare the same to be described in the following specification and accompanying drawings, of which—

Figure 1 is a view of the combined attachment with the buckle and loop part for the winker-stay, showing its operation, the strap being split and inserted in its places without having ends to pass through its two parts, being put in by simply bending each of them right and left. Fig. 2 is a view of the attachment separate from the winker-stay buckle and loop, to be used when the winker-stay buckle is put on in the ordinary way. Fig. 3 is a side view of Fig. 2. Fig. 4 is a longitudinal section of the buckle-tongue and part of the loop for the winker-stay, the section being on a line, $z z$, of Fig. 1.

My invention relates to an overdraw attachment that will enable a person to put in place the leather portions without having to buckle and unbuckle the straps, and can be used with the winker-stay buckle and loop, or can be used separate, as represented in the drawings.

30 A is the winker-stay.

B is the check-rein, split as represented in Fig. 1.

C is the loop and buckle-piece to take the end of the winker-stay.

35 D is the check-rein-attaching device, preferably connected in one piece by bars $a' a'$ with the loop and buckle C.

E is the crown-piece, broken off at each end. a are the holes in the bars $a' a'$, to receive the

40 nails or rivets to fasten the combined check-rein attachment D and winker-stay buckle and loop-piece C to the crown piece E.

45 b is the buckle. c is the tongue. d is a depression in the buckle to receive the tongue, deep enough to be even, or nearly so, with the surface of the buckle.

50 e are projections on the attachment, put on in such manner as to answer the purpose as one continuous bar and allow the straps to be taken in and out without buckling and unbuckling.

f are holes in the single overdraw-piece, for the purpose of riveting or fastening to the crown-piece.

The device D differs from any rein-attaching 55 device to me known, in having the walls $e' e'$ of the same height as and directly opposite the projections $e e$, and extending the whole length of the device, so as to receive wholly within itself the rein.

60 The main object of my invention as above described is to obtain an attachment that can be used with the buckle-piece C or can be used separate, as in Fig. 2, being cheap and easily fastened to the crown-piece, and without the objectionable features that others possess, being ornamental as well as useful.

The depression c for the end of the buckle-tongue b , being made deep enough to receive the end of said tongue, so as to be flush with 70 the surface of the buckle, becomes, in effect, a toe-cap, preventing the forelock-hairs catching into it, as is commonly the case with buckles where they are exposed to the swing of the mane or tail.

75 Splitting the leather, as in Fig. 1, obviates the necessity of having ends, as is the case now.

Having described my invention, what I claim, therefore, is—

80 1. In an overdraw check-rein attachment, the device D, constructed with projections e and wall-elevations e' opposite projections e , substantially as shown, to receive and hold the rein.

85 2. A check-rein attachment, D, combined with the winker-stay buckle and loop-piece C by a connecting-piece, having holes a for riveting to the crown piece E, substantially as described.

90 3. The combination of the split check-rein B with the check-rein attachment D and crown-piece E, all for the purpose specified.

95 4. The combination of the split check-rein B with the check-rein attachment D and the check-strap buckle and loop C, all for the purpose specified.

EDWIN R. CAHOONE.
